D'ARCY AINSWORTH WILLSHAW, OF CARNoustie, SCOTLAND.

APPARATUS FOR GOVERNING AND OPERATING VALVES.

1,066,069.

Specification of Letters Patent.

Patented July 1, 1913.

Application filed March 29, 1912. Serial No. 686,984.

To all whom it may concern:

Be it known that I, D'ARCY AINSWORTH WILLSHAW, a subject of the King of Great Britain and Ireland, residing at Taymouth 5 Engineering Works, Carnoustie, in the county of Forfar, Scotland, have invented new and useful Improvements in Apparatus for Governing and Operating Valves, of which the following is a specification.

10 This invention relates to a type of apparatus for governing and operating admission valves in such a manner that the opening of a valve will be inversely in proportion to the speed of the engine of which the 15 valve is a part.

The invention is applicable to the gas and air admission valves of an internal combustion engine or to any other valve of that type where it is desired to regulate the 20 volume of fluid admitted to the cylinder.

In gas engines the rate of rotation of the crank shaft is determined by the quantity of explosive mixture admitted to the cylinder in a stated period, by the richness of the 25 mixture and by the amount of compression of such mixture before ignition. The quantity of mixture admitted is determined either by the "hit and miss" method, or by varying the amount required for each 30 explosion.

My apparatus is applicable to the two methods of regulating the supply of explosive mixture for internal combustion engines, that is to say the quantity of explosive 35 mixture can be varied for each explosion, or the supply can be entirely cut off for one or more reciprocations of the piston.

In order that my said invention and the 40 manner of putting the same into practice may be properly understood, I have hereunto appended an explanatory sheet of drawings in which the same reference numerals are used to indicate corresponding parts in the figures shown.

45 Figure 1 is a part sectional elevation showing the general arrangement of the apparatus as applied to a gas engine. Fig. 2 is a detail view of the cam roller lever and Fig. 3 is a view looking in the direction of 50 the arrow A, Fig. 2.

In carrying out my invention I use a rotatory ball governor 1 which can cause a lever 2 to rise or fall, this lever being pivoted at 21 to the frame. Suspended at the 55 free end of this lever is a rod 3 and on its lower end is adjustably fixed a setter block

4 which can be made to move up or down on a vertical guide 5 within certain limits by adjusting the jam nuts 22. On a rotatory shaft 6 operated from the engine crank shaft 60 is a single lift cam 7 in touch with a cam roller 8 on a finger lever 9 pivoted to the engine at 10. At the free end of this lever is an adjustable spring plunger 11 whose adjustment can be effected by means of the 65 nuts 12 and 13. In practice I find it advisable to use a second spring plunger 14 similar in design to that first mentioned for the reason that if only one plunger be used the spring 15 has to be so stiff that it may 70 fracture whereas if two spring plungers be used the springs will be subjected to less individual stress. In front of the lever 9 is a similar lever 16 pivoted to the engine at 23 its free end having on it a push knob 17 75 which can be made to come against the stem of the valve 18 and thus open the valve against the pressure of a spring. On the face of this lever 16 and opposite the path of the presser block 4 is an inclined plane 80 19. This plane may be inclined opposite the whole path of the presser block as is shown in the drawings, or for a part at its upper end it may be parallel to the presser guide 5 as shown by the dotted lines Fig. 2. 85

The apparatus operates as follows: The cam 7 when rotating moves forward the finger lever 9 next it, which movement is transmitted through the spring plungers 11 and 14 to the finger lever 16 in front, 90 this lever in turn moving forward and lifting the admission valve 18 off its seat. The amount of valve lift is determined by the position of the setter block 4, which is controlled and operated by the governor 1, relative to the inclined plane 19 on the lever 16 the excess motion if any of the back lever 9 being taken up by the spring plungers. The springs operating the plungers are more than strong enough to open the valve 18. 95 When the setter block 4 is at its lower position as shown by the full lines in Figs. 1 and 2 the engine is running below its normal speed, the inclined plane of the front lever does not come in contact with the block 100 4 and the two levers 9 and 16 can vibrate to the full extent, thus fully openings the valve 18 and when the setter block is at the highest position it is in contact with the inclined or the parallel portion of the plane 105 of the front lever as shown by the dotted lines in Figs. 1 and 2 and the push knob 110

17 cannot operate the valve, the back lever 9 at that time moving as before, the spring plungers also moving out and in due to the want of movement of the front lever. At 5 intermediate positions of the setter block 4 the front lever can move accordingly and through it the valve.

Difficulty is sometimes experienced in throttle governing when rich gas is used as 10 fuel, and the engine on very light load owing to which is termed "back firing" thus necessitating only a minimum lift of the valve. To overcome this difficulty I use the throttle system of governing from 50% upward of 15 the engine load and from 50% downward to no load the hit- and miss- system. This combination is accomplished by the lever 16 having a parallel face for a short distance down the inclined plane.

20 The action is as follows: At half load the setter block 4 is about the position Z. Immediately the setter block passes up beyond the point Z it is impossible for the lever 16 to move forward, thus shutting off the gas 25 from the engine. As the speed of the engine decreases the setter block falls below Z which allows the lever 16 to move sufficiently forward as to open the valve 18 wide enough to admit gas equal to approximately half engine power.

Having now described my invention, what I claim as new and desire to secure by Letters Patent is:—

1. In apparatus for governing and op-

erating valves, in combination, a pivoted lever, a governor in operative connection therewith, a vibratory lever provided with an inclined face and a rigid push knob operatively engaging the valve, a second vibratory lever at the back of the first mentioned vibratory lever and provided with two spring push knobs and a cam roller, said knobs engaging said first mentioned vibratory lever, a rotatory cam actuated by the engine shaft for operating the second 45 lever and through it the first lever and the valve, and a rod adapted to be moved by said pivoted lever, said rod carrying a block adapted to co-act with the inclined face of said first vibratory lever to limit its move- 50 ment.

2. In apparatus for governing and operating valves a vibratory lever provided with an inclined face and a rigid push knob adapted to control the valve in combination 55 with a second vibratory lever placed behind it, said second lever having two spring push knobs engaging said first lever and a cam roller, and engine actuated means adapted to engage said cam roller to actuate said second lever, as described.

In testimony whereof I have signed my name to this specification in the presence of two subscribing witnesses.
